UNITED STATES PATENT OFFICE.

LAWRENCE D. RUTTER, OF WESTFIELD, MASSACHUSETTS, ASSIGNOR OF ONE-HALF
TO GERTRUDE L. RUTTER.

HEADLIGHT-DIMMER.

1,364,812.

Specification of Letters Patent.

Patented Jan. 4, 1921.

Application filed August 14, 1919. Serial No. 317,544.

To all whom it may concern:

Be it known that I, LAWRENCE D. RUTTER, a citizen of the United States, residing at Westfield, in the county of Hampden and 5 State of Massachusetts, have invented certain new and useful Improvements in Headlight-Dimmers; and I do declare the following to be a full, clear, and exact description of the invention, such as will enable others 10 skilled in the art to which it appertains to make and use the same.

My invention relates to improvements in headlight dimmers and more particularly to those employing a plurality of louvers, the 15 present application being in part a continuation of my U. S. application, Serial No. 293,978, filed May 1, 1919.

One object of the invention is to provide novel louvers arranged and operated in a 20 novel manner for either allowing the beam of light to be thrown directly ahead, or for directing an equal volume of light downwardly onto the road and ahead so that the highest ray of the beam of light does not 25 reach a point above a horizontal plane approximately in line with the upper edge of the upper swinging louver of the upper set.

Another object is to prevent the escape of 30 light rays from the reflector around the ends or edges of the louvers when the latter are in deflecting position.

A further object is to provide louvers constructed in a novel manner to deflect the rays of light downwardly.

35 A still further object is to provide a device of the character set forth which may be easily and inexpensively manufactured and marketed, yet one which will be highly efficient and in every way desirable.

40 With the foregoing in view, the invention resides in the novel construction and arrangement of parts hereinafter described and claimed, and shown in the accompanying drawings.

45 Figure 1 is a transverse section of a headlight equipped with the improved dimmer, showing the louvers in open position.

Fig. 2 is a vertical section on the plane of line 2—2 of Fig. 1.

50 Fig. 3 is a transverse section showing the louvers in deflecting position.

Fig. 4 is a vertical section on the plane indicated by line 4—4 of Fig. 3.

Figs. 5 and 6 are transverse sections

through one of the upper louvers, constructed in different ways.

Figs. 7 and 8 are similar views of one of the lower louvers.

In the drawings above briefly described, the numeral 1 designates a ring-like frame 60 preferably formed of a frustum of a hollow cone, said frame being in most instances stamped from sheet metal. A plurality of louvers are mounted in the frame 1 and are adapted to be swung to horizontal positions 65 as in Figs. 1 and 2 to permit the beam of light to be projected straight ahead from the headlight, or to be inclined as indicated in Figs. 3 and 4 for directing the beam of light downwardly on the road. When the louvers 70 are in deflecting position, it is essential that no direct or reflected rays be visible above a plane approximately in line with the source of light, and I have found that if all of the louvers swing in the same direction, it is 75 impossible to shape their ends in such manner as to prevent leakage of rays around said ends when the louvers are inclined for deflecting the rays downwardly. To overcome this difficulty, I employ upper and 80 lower sets of louvers, offset the axes of one set forwardly with respect to those of the other set, and provide means for simultaneously swinging one set of louvers upwardly and the other set downwardly. This permits the ends of all of the louvers to move 85 into tight contact with the frame or ring 1 when said louvers are inclined as in Figs. 3 and 4, and thus no light rays can escape around the ends of said louvers.

In the present showing, the upper set of louvers is indicated by the numeral 2 and the lower set is referred to by the character 3, said louvers 2 being pivoted at their front edges to swing upwardly from horizontal 95 positions, while the louvers 3 are pivoted at their rear edges to swing downwardly from the horizontal. By this relation, the properly contoured ends 4 of the louvers will all strike the frame 1 when said louvers are inclined (see Fig. 3) and consequently no leakage of rays will take place around the ends of said louvers.

The upper set of louvers is shown occupying the greater portion of the upper part of 100 the frame 1 while the louvers 3 occupy the lower part thereof, and when said louvers are in horizontal position the pivot of the

lower louver of the upper set and the pivot of the upper louver of the lower set are spaced apart so that when the louvers are in horizontal position, the aforesaid two 5 louvers will come in as close relation as possible and yet have their respective upper reflecting surfaces parallel. The uppermost of the lower set of louvers may well be provided with a flange 5 which prevents the 10 direct forward escape of light rays when the louvers are in the deflecting position illustrated in Fig. 4. The portion of the frame 1 above the upper set of louvers may well be occupied by a fixed louver 2^a.

15 I intend that the lower surfaces of the two sets of louvers shall be silvered or of some similar character, while the upper surfaces of said louvers may be of any color, although brass or gold is desired; and all of 20 these surfaces except the lower surface of the lowermost louver 3 and possibly the upper surface of the louver 2^a, will be suitably polished to readily reflect the rays of light from the usual reflector R. By this arrangement, 25 when the louvers are inclined, the rays of light from the reflector will strike the silvered or other reflecting lower surfaces of said louvers and will be reflected downwardly onto the upper surfaces of the louvers 30 directly beneath. These upper surfaces reflect the rays forwardly and according to the relative angle which the two reflecting surfaces form to each other, may be controlled so that the highest ray from the main 35 beam of light does not reach a point from the road which is above the upper edge of the upper swinging louver of the upper set and such light will not blind the drivers of approaching vehicles and is directed in a 40 manner to comply with all laws.

To throw the light downward which is not possible when the upper surface of each louver is parallel with the lower surface of the louver directly above, I dispose these 45 surfaces in rearwardly converging relation as emphasized by the two lines L of Fig. 4. By this arrangement, the rays of light strike the lower surfaces of the louvers at a more acute angle in relation to this surface than 50 otherwise and are deflected from said surfaces at the same angle in relation to this reflecting surface, strike the upper surfaces of the louvers below more acutely in relation to this reflecting surface than would 55 otherwise take place and consequently leave said upper surfaces in a direction which insures that no blinding effect shall be produced above a point from the road which is level with the upper edge of the upper 60 swinging louver of the upper set.

The louvers, as shown, comprise upper and lower metal leaves 19 and 20 forming reflecting surfaces.

In Fig. 5, one of the louvers 2 is shown, 65 constructed of a single sheet of metal, said

sheet being folded substantially upon itself at 21^b to form converging upper and lower leaves 19^a and 20^a. The edges of these leaves remote from the bend 21^b are secured together by clenching one of the leaves around the other and at the same time forming a tubular bead 21^c. Fig. 6 discloses one manner of forming the louvers 2 from two separate sheets of metal, one of said sheets forming the upper leaf 19 while the other 70 sheet constitutes the lower leaf 20. The edges of the leaves 19 and 20 are secured together by clenching as shown at 21 and 21^a, and the latter connection forms also a tubular bead. The construction shown in Fig. 80 75 is illustrated in the general views.

In Fig. 7, I have shown one of the louvers 3 formed from a single metal plate bent upon itself at 21^e to form the upper and lower leaves 19^b and 20^b. The edges of the leaves 85 19^b and 20^b are suitably secured together opposite the bend 21^e and are provided with an appropriate tubular bead 21^d. In Fig. 8, one of the louvers 3 is shown constructed of two separate sheets of metal constituting 90 upper and lower leaves 19^c and 20^c, the edges of said leaves being secured together by clenching as shown at 21^e and 21^f, the latter connection forming also a tubular bead. This construction is shown in the general 95 views.

The reflecting surfaces of the leaves 19 and 20 of each louver diverge rearwardly and it is due to this formation that the upper reflecting surface of each louver is disposed 100 in rearwardly converging relation with the lower reflecting surface of the louver directly above. The reflecting surfaces of the leaves 19 and 20 must be highly polished or otherwise treated to reflect the rays of light 105 in the required manner, and if desired the upper and lower surfaces may be of different colors. For instance the lower reflecting surface formed on leaf 20 may be finished in some silver color and the upper reflecting 110 surface formed on leaf 19 may be of a yellow or gold color. Thus, when the two surfaces are polished, the lower surface will present a silvered reflecting upper surface and the upper surface will possess a gold like 115 surface which will soften the rays of light without decreasing the strength of the beam.

Although any adequate means could be employed for operating the louvers 2 and 3, I prefer to use the arrangement shown. A 120 lever 6 is fulcrumed between its ends at one side of the frame 1, preferably at the low side of said frame, and although said lever is shown mounted on an ear 7, it could be fulcrumed in any preferred manner. 125 Suitable linkage connects one end of lever 6 with one set of louvers, while other linkage is employed to connect the other end of said lever with the other set of louvers. This linkage may vary as occasion may dictate, 130

but for ease and inexpensive manufacture, I prefer to connect the free front edges of the lower louvers 3 by a wire 8, while the rear edges of the upper louvers 2 are similarly connected by a wire 9. The louvers are formed with openings 10 (see Fig. 3) and the wires 8 and 9 are looped through said openings as indicated at 11. A wire link 12 depends from the lowermost louver 2 to the rear end of the lever 6, the upper end of said link being looped through an opening in said louver, and a similar but relatively short link 13 connects one of the lower louvers 3 with the lever 6. A wire control 14 similar in principle to the Bowden wire control is by preference employed for operating the lever 6 and may lead to any convenient point for manipulation. The tubular casing 15 of the control wire 14 may extend through the usual glass lens G or through the headlight casing, as desired.

The dimmer may be installed in numerous forms of headlights and may of course be constructed in different sizes and in some instances the device may well be built into the headlight as manufactured, in which case the reflector or some other suitable part would set as the frame 1 for supporting the louvers. In the construction shown, the frame 1 diverges rearwardly to a noticeable extent with respect to the reflector and this serves to prevent the possible escape of objectionable reflected rays from the headlight reflector below the lowermost of the louvers.

3. The inner side of the frame 1 does not constitute a reflecting surface nor does the lower side of the lowermost louver and consequently no blinding rays will be reflected from these parts. The contracted rear end of the frame 1 is shown provided with spring tongues 23 which are bent so as to form a yielding contact with the reflector R. This detail of construction permits one size of dimmer to be installed upon headlights of slightly varying sizes and upon those in which the reflector possesses different curvatures.

The entire device may be easily and inexpensively manufactured and marketed, may be easily installed, and will be highly efficient and in every way desirable. Particular attention is directed to the fact that the two sets of louvers swing in opposite directions; to the rearwardly converging reflecting surfaces of the adjacent louvers; to the novel construction and operating means of said louvers; and to the arrangement of spring tongues for centering the dimmer in reflectors of different sizes and shapes. These several features are by preference carried out in the manner shown, but within the scope of the invention as claimed, numerous minor changes may well be made.

I claim:

1. In a headlight dimmer, a frame, two

sets of horizontally pivoted louvers in said frame, and means for simultaneously swinging the louvers of the two sets in opposite directions.

2. In a headlight dimmer, a frame formed of a frustum of a hollow cone, an upper set of louvers in said frame pivoted at their front edges to swing upwardly from horizontal positions, a lower set of louvers in said frame pivoted at their rear edges to swing downwardly from horizontal positions, and means for simultaneously operating the two sets of louvers.

3. In a headlight dimmer, a frame, a plurality of sets of louvers in said frame, the pivots of each set being laterally offset from those of the next set, a lever fulcrumed between its ends at one side of said frame, linkage connecting the front edges of the lower louvers with the front end of said lever, additional linkage connecting the rear edges of the upper louvers with the rear end of said lever, and means for operating said lever.

4. In a headlight dimmer, a circular frame, an upper set of louvers in said frame pivoted at their front edges to swing upwardly from horizontal positions, a lower set of louvers in said frame pivoted at their rear edges to swing downwardly from horizontal positions, the free edges of all of said louvers having openings, wires looped through the openings of the two sets of louvers for moving them in unison, a lever fulcrumed at the lower side of the frame and operatively connected to the lower set of louvers, a wire connecting said lever with the upper set of louvers, and means for operating said lever.

5. In a headlight dimmer, a frame, upper and lower sets of pivoted louvers having reflecting surfaces on their upper and lower sides, the upper reflecting surface of each louver converging rearwardly with the lower reflecting surface of the louver directly above, and means for simultaneously swinging one set of louvers upwardly and the other set downwardly.

6. In a headlight dimmer, a frame, and a plurality of vertically spaced louvers mounted in said frame, each louver having reflecting surfaces on its upper and lower sides diverging rearwardly with respect to each other, whereby the upper reflecting surface of each louver is disposed in rearwardly converging relation with the lower reflecting surface of the louver directly above.

7. In a headlight dimmer, a frame, and a plurality of vertically spaced louvers mounted therein, each louver being formed of thin sheet metal and having rearwardly diverging upper and lower reflecting surfaces.

8. In a headlight dimmer, a frame, a plurality of sheet metal louvers in said frame formed of upper and lower leaves formed

4
with reflecting surfaces, said leaves diverging rearwardly and secured together at their edges, one leaf of each louver being bent at one edge to form a bead, and pivots carried by said frame and received in the beads of the several louvers.

9. In a headlight dimmer, a frame formed of a frustum of a hollow cone, said frame being adapted for reception in the reflector 10 of a headlight, spring tongues on the rear

edges of said frame shaped to form a yielding contact with the reflector, upper and lower sets of pivoted louvers mounted in said frame, and means for simultaneously swinging one set of louvers upwardly and 15 the other set downwardly.

In testimony whereof I have hereunto set my hand.

LAWRENCE D. RUTTER.
